ATTORNEY

UNITED STATES PATENT OFFICE.

WILLIAM CARROLL WITT, JR., OF JONESBOROUGH, TEXAS.

DITCHING-MACHINE.

SPECIFICATION forming part of Letters Patent No. 439,739, dated November 4, 1890.

Application filed August 4, 1890. Serial No. 360,929. (No model.)

To all whom it may concern:

Be it known that I, WILLIAM CARROLL WITT, Jr., a citizen of the United States, residing at Jonesborough, in the county of C^oryell and State of Texas, have invented certain new and useful Improvements in Ditching-Machines; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention has relation to ditching-machines; and it consists in the novel construction and arrangement of its parts.

In the accompanying drawings, Figure 1 is a side elevation of my invention. Fig. 2 is a top plan view. Fig. 3 is a sectional view of Fig. 1.

My invention is described as follows: It consists of the plow-standards A, the front ends of which are fastened securely to a block a, and the rear ends are fixed to the body of the scoop B. Said standards have rigidly attached to them a pair of handles a'. Said handles are firmly braced by bars a² and a cross-round a³. Extending downward from said standards A, near their front ends, is a pair of ears a⁴, between which is journaled an axle a⁵. Said axle has a wheel a⁶, provided with cogs a⁷, rigidly attached to it.

The scoop B consists of the points b and the chute b', fastened together by side plates b². Said plates are slightly bent in at their upper edges, so as to bunch the earth.

Immediately in the rear of the scoop B is an elevator-shaft C, the upper end of which rests on the round a³. In said shaft works an endless band c, provided with elongated cups c'. Said band passes around a roller c², journaled in the body of the scoop B and over a roller c³, journaled at the upper end of the elevator-shaft C and between the two sides of the same.

One end of the axle on which roller c³ rotates is provided with a cog-wheel c⁴, which acts in conjunction with cog-wheels d and c⁵.

Said cog-wheel c⁵ is rigidly attached to one end of a shaft c⁶, on the other end of which is rigidly secured a cog-wheel c⁷, which works

in the cogs a⁷ of the wheel a⁶. In the rear of said roller c³, and a little below the same, seated in the arms d', which extend from the elevator-shaft C, is a chute D. Said chute is considerably inclined, and is provided with an endless band d², which passes over a couple of rollers d³. Said rollers and band are operated by the cog-wheel d, that meshes with cog-wheel c⁴.

My invention is operated as follows: I apply the motive power to my ditcher and let the point of the scoop enter the earth and let wheel a⁶ run along over the ground. As the wheel a⁶ rotates, the cog-wheel c⁷, working in the cogs a⁷ of said wheel a⁶, will revolve the shaft c⁶, which in turn will revolve the cog-wheel c⁵. As said wheel c⁵ rotates, it revolves the wheel and roller c⁴ and c³. This carries the band up and around the two rollers c³ and c². When the cog-wheel c⁴ revolves, it rotates the cog-wheel d. This moves the rollers d³ and causes the band d² to move around them. As the scoop passes along, the dirt is thrown upon the endless band c, and with the aid of the elongated cups c' it is carried to the top of the elevator-shaft, and the traveling band will then throw it over into the chute D, and when in said chute it will either slide down the incline or will be carried by the band d² to the lower edge of the chute and thrown on one side of the ditch.

Having described my invention, what I claim as new, and desire to secure by Letters Patent, is—

A ditcher consisting of the standards A, block a, handles a', braces a², and round a³, ears a⁴, axle a⁵, and wheel a⁶, having cogs a⁷, scoop B, provided with points b, chute b', and side plates b², elevator-shaft C, its upper end resting on the round a³, band c, elongated cups c', rollers c² and c³, cog-wheels c⁴, c⁵, and c⁷, shaft c⁶, inclined chute D, cog-wheel d, arms d', band d², and rollers d³, all substantially as shown and described, and for the purposes set forth.

In testimony whereof I affix my signature in presence of two witnesses.

WILLIAM CARROLL WITT, JR.
